(57) **CLAIM**

The ornamental design for an illuminatable device, as shown and described.

DESCRIPTION

FIG. 1 is a perspective view of an illuminatable device for placement proximate to a windshield of a vehicle or a suitably dimensioned window environment, under a first embodiment.

FIG. 2 is a top view of the illuminatable device of FIG. 1. FIG. 3 is a bottom view of the illuminatable device of FIG. 1.

FIG. 4 is a front view of the illuminatable device of FIG. 1. FIG. 5 is a back view of the illuminatable device of FIG. 1. FIG. 6 is a left side view of the illuminatable device of FIG. 1.

FIG. 7 is a right side view of the illuminatable device of FIG. 1.

FIG. 8 is a perspective view of an illuminatable device for placement proximate to a windshield of a vehicle or a suitably dimensioned window environment, under a second embodiment.

FIG. 9 is a top view of the illuminatable device of FIG. 8. FIG. 10 is a bottom view of the illuminatable device of FIG. 8.

FIG. 11 is a front view of the illuminatable device of FIG. 8.

FIG. 12 is a back view of the illuminatable device of FIG. 8.

FIG. 13 is a left side view of the illuminatable device of FIG. 8; and,

FIG. 14 is a right side view of the illuminatable device of FIG. 8.

The broken lines shown in the drawings are for the purpose of illustrating the environment of the illuminatable device, and form no part of the claimed design.

1 Claim, 6 Drawing Sheets
